UNITED STATES PATENT OFFICE.

CHARLES H. OVERKAMP, OF CINCINNATI, OHIO, ASSIGNOR TO THE TRIUMPH MANUFACTURING COMPANY, OF CINCINNATI, OHIO, A CORPORATION OF OHIO.

LOAF-FORMING MACHINE.

No. 901,030.

Specification of Letters Patent.

Patented Oct. 13, 1908.

Application filed October 28, 1907. Serial No. 399,492.

To all whom it may concern:

Be it known that I, CHARLES H. OVERKAMP, a citizen of the United States, residing at Cincinnati, Ohio, have invented a new and useful Improvement in Loaf-Forming Machines, of which the following is a specification.

My invention relates to loaf forming machines of the class adapted to the use of bakers or others for forming loaves of bread, buns, etc. and the objects of my improvements are to provide means for shaping predetermined quantities of dough or other plastic material into substantially spherical forms; to provide means for kneading the material during its shaping process; to provide interchangeable means for driving the endless apron either continuously or intermittently as desired; to provide means for moving the forming board and the apron intermittently in unison; to provide means for simultaneously or for independently adjusting the extent of the movement of both the forming board and of the apron; to provide adjustable bearings for the apron guide roller, and to provide simple and durable construction and such assemblage of parts as will secure the greatest facility of operation and efficiency of action. These objects are attained in the following described manner as illustrated in the accompanying drawings, in which:—

Figure 1, is a front elevation with parts broken away of a loaf forming machine embodying my improvements; Fig. 2, an end elevation with parts removed; Fig. 3, a transverse section on the line $a-a$ of Fig. 1, and Fig. 4 an elevation with parts in section of the pawl and ratchet mechanism.

40 In the drawings, 1 represents the horizontal table supported on legs 2 and formed with a longitudinal offset 3 in the rear portion of its surface. An endless apron 10 preferably of canvas is carried on vertical driving and guide rollers 4 and 5 with its lower front edge in contact with the offset 3. The driving roller 4 is journaled at its respective ends in one end of the table and in a bracket 6 which is secured on the table, and the guide roller 5 is journaled in bearings 7 and 8 which are independently adjustable by means of hand screws 9 in the opposite end of the table and in stationary bracket 11.

45

50

55 A stationary guide board 12 secured on the table serves to maintain the front por-

tion of the apron in the same vertical plane and to prevent it from yielding rearwardly under the pressure of the dough on its surface. Shaft 13 journaled in bracket 14 and in one of the supporting legs is provided with a driven pulley 15, and an eccentric 16. A spur gear 17 splined on said shaft is movable longitudinally thereon by means of a yoke lever 18 in the usual manner. The main shaft 19 journaled in the supporting legs 2 is provided with a spur gear 21 which engages with gear 17 and transmits motion to the roller 4 by means of miter gears 22.

A rock shaft 23 journaled in the end supporting legs and parallel with the main shaft is provided with crank arms 24 and with a rocker arm 25 which is extended therefrom in opposite directions and is formed with slots 26 and 27 in its respective end portions. An eccentric rod 28 actuated by the eccentric 16 is adjustably secured at one end in slot 26 for imparting a rocking motion to shaft 23. Brackets 31 slidingly mounted in guides 32 which are secured on the under side of the table are reciprocated in unison from the crank arms 24 by means of connecting rods 33. A forming board 34 preferably faced with canvas or kauried and provided with a knife 35 in movable contact with the surface of the table is adjustably secured to the brackets at different inclined angles to the table in front of and with its edge longitudinally parallel with the apron.

A gravity forming board 36 pivotally connected with stationary brackets 37 by means of parallel links 38 is free to swing in a vertical plane and in positions parallel with both the table and the apron, said board is slanted laterally with its face over and substantially perpendicular to a plane which bisects the angle between the face of the apron and the forming board 34. A fixed stop 39 limits the downward swing of board 36 by contacting with one of the links. A stationary apron 41 attached to the discharge end of the table serves to receive the loaves after they are formed.

A rack 42 adjustably secured in slot 27 of the rocker arm 25 engages with a flanged pinion 43 which is idly mounted on the main shaft 19. Said pinion carries a pawl 44 adapted to engage with a ratchet wheel 45 which is secured on said shaft and whereby said shaft may be rotated intermittently for driving the apron in unison with the rear- 110

ward movements of the forming board. A flour sifter (not shown) may be supported above the table and automatically actuated by means connected with any of the moving members of the machine.

In operation, when it is desired to run the apron continuously, the pawl should be secured out of engagement with the ratchet wheel, or the rack and pinion disconnected and the gear 17 engaged with the gear 21. For driving the apron intermittently, the rack and pinion mechanism should be used and gear 17 disengaged from gear 21 as shown by dotted lines in Fig. 1. Predetermined quantities of dough successively placed on the front end of the table are repeatedly pressed against the apron by the movement of the forming board and simultaneously rolled in a rearward direction by the apron and under the weight of the gravity forming board whereby they are kneaded and formed into spherical shapes then discharged on the receiving apron.

The apron guide roller serves also to keep the apron under proper tension. The movement of the forming board may be changed by the adjustment of the eccentric rod in slot 26, and the intermittent movement of the apron may be changed by the adjustment of the rack in slot 27 as desired.

Having fully described my improvement, what I claim as my invention and desire to secure by Letters Patent of the United States is:—

35. 1. A loaf forming machine comprising an endless apron, means for moving it intermittently, a forming board longitudinally parallel with and laterally inclined in relation to the apron, and means for reciprocating the board in a direction perpendicular to the apron and in unison with its movements.

2. In a loaf forming machine, the combination of a driven shaft, an endless apron, interchangeable means actuated by the shaft for driving the apron either continuously or intermittently a forming board parallel with the apron, and means for reciprocating it in a direction perpendicular thereto.

3. In a loaf forming machine, the combination of a table, vertical rollers thereon, an endless apron carried by the rollers, a forming board parallel therewith and ad-

justable in different vertical angles, and mechanism for simultaneously moving the apron and reciprocating the board in a direction perpendicular thereto.

4. The combination of a table, a forming board movable thereon, a rock shaft provided with an arm, connections between the shaft and the board, a driven shaft, an eccentric thereon and connections therewith adjustably secured on the arm.

5. The combination of a horizontal table, a vertical roller thereon, an endless apron carried by the roller, an inclined forming board mounted on the table parallel with the apron, a gravity board swingingly depending from fixed points and between the apron and said forming board, and adjustable driven mechanism for driving the roller with the apron and simultaneously reciprocating the forming board laterally in a horizontal plane.

6. A loaf forming machine comprising parallel walls, the one being vertical, the other adjustable in different vertical angles, means for moving the former wall longitudinally in a horizontal plane and for reciprocating the latter wall laterally in a horizontal plane.

7. A loaf forming machine comprising a horizontal table, a vertical wall movable longitudinally thereon, an inclined wall parallel therewith and movable laterally on the table, and means for moving said walls simultaneously.

8. A loaf forming machine comprising parallel vertical and inclined walls and means for moving the one longitudinally and simultaneously reciprocating the other laterally.

9. A loaf forming machine comprising a table, a vertical apron movable longitudinally thereon, an inclined wall parallel with the apron and means for moving the apron intermittently and reciprocating the wall laterally and in unison therewith.

In testimony whereof witness my signature at Cincinnati, Ohio, this 26th day of October, 1907.

C. H. OVERKAMP.
